SUCTION CLEANER

Louis E. Segesman, Canton, Ohio, assignor to The Hoover Company, North Canton, Ohio, a corporation of Ohio

Application June 13, 1945, Serial No. 599,147

5 Claims. (Cl. 183—54)

1

The present invention relates to suction cleaners in general and more particularly to a new and improved filter-cleaning mechanism in a suction cleaner. More specifically the invention comprises a tank type cleaner which is adapted to be placed upon end and thereafter the dirt filter vibrated to dislodge adhering foreign material which may thereupon drop onto the underlying supporting surface.

It is a purpose of the present invention to provide a new and improved suction cleaner. It is another object of the invention to provide new and improved bag-cleaning means in a suction cleaner. A still further object of the invention is to provide a tank type suction cleaner which is adapted to be placed upon its open end, after the removal of its cover plate, and thereafter have its filter bag vibrated by operator-operable means. Still another object of the invention is to provide a tank type suction cleaner in which means are provided by which the enclosed bag may be violently agitated by an operator-supplied force to the end that collected foreign material may drop from the bag through the open mouth thereof and onto an underlying surface covering, the cleaner being supported upon its open end. A further object of the invention is to provide a new and novel unitary bag-shaking mechanism adapted to be positioned within the main casing of a suction cleaner upon the removal of the removable end cap thereof. These and other more specific objects will appear upon reading the following specification and claims and upon considering in connection therewith the attached drawings to which they relate.

Referring now to the drawings in which a preferred embodiment of the invention is disclosed:

Figure 1 is a longitudinal vertical section through a cleaner constructed in accordance with the present invention;

Figure 2 is a vertical transverse section upon the line 2—2 of Figure 1;

Figure 3 is a view in perspective of the bag-shaking structure removed from the cleaner;

Figure 4 is a partial top view of the structure shown in Figure 3;

Figure 5 is a partial bottom view of the cleaner showing the operator-operable foot pedal.

In the drawings the outer elongated main casing of the cleaner is indicated by the reference character 1. One end of casing 1 is permanently closed by a cover or cap 2 which is permanently secured in place and which is provided with a dusting tool-connecting port 3. The opposite end of casing 1 is closed by a removable cap 6 which

2

is provided with an intake port 7 adapted to receive and seat the cleaner end of a dusting tool unit in the same manner as port 3. The cover 6 is removably retained in place on the casing by being provided at its lowermost point with a protruding lip 8 which seats within a receiving pocket 9 formed at the end of a bracket 11. A manually operable latch 12, of the overcenter type, is provided at the top of the cleaner casing and is adapted to cooperate with the top portion of cover 6 to force that element against the end wall or face 13 of the machine, a suitable resilient seal 14 being provided to prevent leakage of air.

Casing 1 is slidably supported upon longitudinally extended runners 16 of a common and well known type which enable the operator to pull the machine over the supporting surface by means of a force exerted through the dusting tool hose. There is also provided along the top of the cleaner casing a handle 17 which is preferably of the strap type and which provides means by which the operator can lift the cleaner from place to place.

Within casing 1, and near the end thereof closed by the end cap 2, is a motor-fan unit. The motor is indicated at 21 and the shaft 22 thereof extends into the fan chamber 23 where it carries the rotatable fans 24 which are separated by a fixed guide vane structure 26. The fan chamber is formed with an intake port 27 and with exhaust ports 28. The unit is supported at its forward end by means of a resilient rubber ring 29 which lies around the forward edge of the fan chamber 23 and which is itself supported by a fixed bulkhead 21 in the casing 1. At its opposite end the motor-fan unit is carried by a second resilient ring indicated at 32 which encircles the hub of the motor casing 21 and which is itself carried by a perforated bulkhead element 33 fixedly secured in casing 1. The forward bulkhead 31 is also perforated and is contoured to provide a shoulder 34 which seats and frictionally retains a perforated cap 36 to form a chamber 37 within which is positioned suitable filtering material to provide a secondary filter, the primary filter being an ordinary filter bag as will be described.

On the suction side of the motor-fan unit, and between the bulkhead 31 and the cover 6, is positioned the principal filter of the cleaner comprising an air-permeable dirt bag 41. The open end of bag 41 is secured to a flange 42 which defines a central aperture through the end plate or ring 13. The opposite end of the bag is similarly secured to an inner bag ring 43 from the opposite sides of which brackets 48 extend. Arms 46 and

47 pivotally connect to each bracket 48 and are also pivoted at their lower ends to a base plate 51 which lies along the lower portion of the casing 1 and which is fixedly secured, as by welding, to the forward bag ring 13. Base plate 51 is materially lightened as by punching a plurality of holes therethrough and is formed on two levels, the lower level lying upon the casing 1 while the upper level is spaced thereabove. Base plate 51 is secured relative to the bottom of casing 1 by one or more spring clips 52, illustrated in Figure 1. It should be pointed out that the pivoted arms 46 and 47 are equal in length and have their pivot points at their opposite ends spaced equidistant so that as the arms pivot the bracket elements 48 at all times remain parallel to the major longitudinal axis of the cleaner which results in the bag ring 43 also remaining parallel with the bag ring 13 at the opposite end of the filter 41.

Arms 46 are interconnected below their pivots upon the base plate 51 and a coil spring 56 is connected thereto and at its opposite end to a plate 57 permanently secured upon the top of base plate 51. Spring 56 exerts a force which tends at all times to move arms 46, and accordingly connected arms 47 and bag ring 43, rearwardly within the casing 1 and to draw the bag 41 taut. The side edge of plate 57 is turned upwardly at an angle and cooperates with a guide plate 61, which is suitably secured as by screws 62, to form a longitudinally directed guideway within which is mounted for sliding movement a slide 64 which carries a roller contact 66 at its end. Slide 64 is connected by a stiff wire or rod 67 to the pivoted arm 47 so that the two elements can only move simultaneously. Movement of the slide 64 toward the end ring 13 functions to pivot the pairs of arms 46 and 47 and to stretch the coil spring 56 thereby permitting the bag 41 to grow slack. Clearly a sudden release of the slide 64 will permit the coil spring 56 to jerk the pivoted arms and the bag ring 43 to their initial positions, drawing the bag 41 taut.

To effect the movement of the slide 64 there is provided a pivoted lever 71 carried upon the upper surface of the upper level of base plate 51. Lever 71 is provided with a downwardly extending shoulder 72 which passes through a slot 73 formed in plates 51 and 57. Upon pivoted lever 71 and carried thereby is a pivoted pawl 76 which is at all times pivoted in a clockwise direction, as viewed in Figures 3 and 4, by a spring 77. The pawl 76 is formed with a sloping forward end adapted to contact the roller contact 66 on the slide 64 and is so contoured and shaped that, as the lever 71 pivots in a counterclockwise direction as viewed in Figures 3 and 4, the pawl will move the slide 64 against the tension exerted by spring 56, until such time as it shall move in its curved path beyond and inside of the contact 66. The release of the contact 66 permits the coil spring 56 to jerk the pivoted arms 46 and 47, the carried bag ring 43, and the slide 64 back to their initial positions.

A pivoted foot pedal or lever 81 is provided upon the underside of the casing 1, being keyed to a pin 82 which extends within the casing to be keyed to lever 83, the extremity of which abuts the depending shoulder 72 upon the pivoted lever 71. Lever 83 is at all times held in its retracted position, illustrated in Figures 3 and 4, by means of a second coil spring 84 connected to the afore-described lever 76. The force of the spring is transmitted from lever 76 to lever 83 through the

abutting shoulder 72. Similarly, an operator-applied force upon the pedal 81 effects the pivotal movement of the lever 71 and so the pawl 76 within the casing 1. Release of the operator-applied force upon the pedal 81 permits the spring 84 to return the lever 71 and pawl 76, together with the pedal 81, to their initial positions.

The operation of the cleaner constructed in accordance with the present invention may be described as follows: In normal cleaner operation dirt-laden air is drawn through a suitable dusting tool unit connected to the intake port 7 in the cover 6 and passes into the filter bag 41. Filter 41 removes from the air stream the suspended foreign material and the clean air passes outwardly through the wall of the bag and into the space defined by the surrounding main casing 1. Before entering the fans, which are rotated by the motor 21, the air first passes through the secondary filter 37 to remove any remaining particles which may have escaped from the initial separator 41. The cleaned air passes into the fan system at the intake or eye 27 of the fan chamber 23 and is exhausted, after passing through the fans 24 and the guide vane element 26, at the exhaust ports 28 into the space within the casing 1 surrounding the motor 21. This space is separated from the space around the filter bag 41 by the bulkhead 31. The air then passes through the foraminous bulkhead 33 and outwardly into the surrounding atmosphere via the exhaust port 3 in the permanently attached cover 2. This operation can continue until such time as the accumulation of foreign material within the filter bag 41 reduces the effective suction of the machine thereby reducing cleaner efficiency. Thereupon it becomes desirable to remove the foreign material from the bag.

The bag-cleaning operation comprises initially the removal of the end cap 6. This is accomplished by the operator releasing the cover latch 12 whereupon the cover 6 pivots outwardly at its upper end to permit the downwardly extending lip 8 on the underside thereof to disengage its socket 9. The cleaner is then open ended and the operator tilts it so that ring or plate 13 lies flush upon the supporting surface which is preferably provided with a receiving paper or the like. With the machine so positioned the pedal 81 extends substantially horizontally and is positioned near the lower end of the machine. Also, the bag 41 is arranged with its open mouth facing downwardly.

To dislodge the foreign material from the bag and to clean it the operator now exerts a downward pressure upon the pedal 81 which results in the pivotal movement of the lever 71 and the pawl 76 carried thereby. As previously described, the movement of the pawl 76 brings it into contact with the roller 66 whereupon the slide 64 moves toward the ring 13 and effects the pivotal movement of the supporting arms 46 and 47 of the bag ring 43. This movement of bag ring 43 provides a slack within the bag which increases until the pawl 76 rides under and past the roller contact 66, due to its curved path of travel. Thereupon the coil spring 56 jerks the bag ring 43 back to its original position in which the bag was taut, this being accomplished by the pivotal force which it exerts upon the arms 46. This abrupt vibration of the bag effects the dislocation of adhering foreign material which thereupon falls downwardly through the central aperture of bag ring or plate 13 to rest upon the underlying supporting surface. The bag-shaking op-

eration should be repeated a plurality of times to insure complete cleaning of the bag.

After the bag has been adequately cleaned the operator need only tilt the machine back into its original operating position, replace the cover 6 in the obvious manner, and the machine is again ready for cleaning operation.

I claim:

1. In a suction cleaner, an elongated casing, means to support said casing movably with its major axis extended horizontally, a removable cover for the end of said casing, said casing, with said cover removed, presenting an open end adapted to seal upon a supporting surface to support said casing with its major axis extended vertically, a filter bag in said casing with its open end opening toward the open end of said casing, a frame supporting the closed end of said bag, frame-supporting means movably supporting said frame, spring means exerting a force to move said frame from said open end to draw taut the side wall of said bag, a slide connected to said frame-supporting means, a pivoted lever movable to slide said slide to move said frame-supporting means toward said open end, said lever being adapted to release said slide so that said spring means can return said frame-supporting means to its original position abruptly to dislodge collected foreign material, and means on the outside of said casing to actuate said lever.

2. In a suction cleaner, an elongated casing, means to support said casing movably with its major axis extended horizontally, a removable cover for the end of said casing, said casing, with said cover removed, presenting an open end adapted to seal upon a supporting surface to support said casing with its major axis extended vertically, a filter bag in said casing with its open end opening toward the open end of said casing, a frame supporting the closed end of said bag, frame-supporting means movably supporting said frame, spring means exerting a force to move said frame from said open end to draw taut the side wall of said bag, a slide connected to said frame-supporting means, a pivoted lever movable to slide said slide to move said frame-supporting means toward said open end, said lever including a pivoted spring-urged pawl adapted to release said slide after a predetermined movement, second spring means urging said lever to its initial position upon the removal of the pivoting force thereon, said pawl pivoting against the force of its spring as it moves past said slide, and a pedal on the exterior of said casing to pivot said lever.

3. In a suction cleaner, an elongated casing, means to support said casing movably with its major axis extended horizontally, a removable cover for the end of said casing, said casing, with said cover removed, presenting an open end adapted to seal upon a supporting surface to support said casing with its major axis extended vertically, a filter bag in said casing with its open end opening toward the open end of said casing, a frame supporting the closed end of said bag, frame-supporting means movably supporting said frame, spring means exerting a force to move said frame from said open end to draw taut the side wall of said bag, a slide connected to said frame-supporting means, a pivoted lever movable to slide said slide to move said frame-supporting means toward said open end, said lever including a pivoted spring-urged pawl adapted

to release said slide after a predetermined movement, second spring means urging said lever to its initial position upon the removal of the pivoting force thereon, said pawl pivoting against the force of its spring as it moves past said slide, a pedal on the exterior of said casing to pivot said lever, a base plate slidable into said casing through said open end and mounting said frame, frame-supporting means, spring means, slide and lever as a removable unit, and means to retain said unit in said casing.

4. In a suction cleaner, an elongated casing, means to support said casing movably with its major axis extended horizontally, a removable cover for the end of said casing, said casing, with said cover removed, presenting an open end adapted to seal upon a supporting surface to support said casing with its major axis extended vertically, a filter bag in said casing with its open end opening toward the open end of said casing, a base plate below said filter supported by said casing, a rigid bag ring at one end of said plate holding the open end of said bag distended and forming the open end of said casing, a frame at the closed end of said filter, frame-supporting means mounting said frame on said plate for movement toward and from said open end, spring means between said frame-supporting means and said plate exerting a force to draw said bag taut, a slide on said plate connected to said frame-supporting means, a pivoted lever on said casing to move said slide to move said frame-supporting means toward said open end, and a pedal on the outside of said casing to actuate said lever.

5. In a suction cleaner, an elongated casing, means to support said casing movably with its major axis extended horizontally, a removable cover for the end of said casing, said casing, with said cover removed, presenting an open end adapted to seal upon a supporting surface to support said casing with its major axis extended vertically, a filter bag in said casing opening toward said open end of said casing, a unit removable as such from the open end of said casing and including means to support and means to shake said bag, and an operator-operable pedal carried by the exterior of said casing and connected to said means to shake said bag and adapted to receive an actuating force to operate said means to shake said bag.
